UNITED STATES PATENT OFFICE

112,616

DESIGN FOR A MEASURING SPOON OR SIMILAR ARTICLE

Theodore Pratt, Glen Cove, and Rudolph Schumacher, Jr., Bronx, N. Y.; said Schumacher assignor to said Pratt

Application October 20, 1938, Serial No. 80,578

Term of patent 14 years

To all whom it may concern:

Be it known that Theodore Pratt, a citizen of the United States, residing in Glen Cove, in the county of Nassau and State of New York, and Rudolph Schumacher, Jr., a citizen of the United States and residing in the Borough of the Bronx, county of Bronx, and State of New York, have invented a new, original, and ornamental Design for a Measuring Spoon or Similar Article, of which the following is a specification, reference being had to the accompanying drawing, forming a part thereof, wherein:

Fig. 1 is a top plan view of a measuring spoon or similar article showing our new design; and
Fig. 2 is a side view of a measuring spoon or similar article.

We claim:

The ornamental design for a measuring spoon or similar article, as shown.

THEODORE PRATT.
RUDOLPH SCHUMACHER, JR.
